UNITED STATES PATENT OFFICE.

HARRY C. BUHOUP, OF CHICAGO, ILLINOIS.

DRAFT-RIGGING FOR RAILWAY-CARS.

SPECIFICATION forming part of Letters Patent No. 668,574, dated February 19, 1901.

Application filed November 8, 1900. Serial No. 35,824. (No model.)

To all whom it may concern:

Be it known that I, HARRY C. BUHOUP, a citizen of the United States, residing at Chicago, in the county of Cook, State of Illinois, 5 have invented certain new and useful Improvements in Draft-Rigging for Railway-Cars; and I hereby declare the following to be a full, clear, and exact description of the same, reference being had to the accompanying 10 drawings, in which—

Figure 1 is a horizontal section of draft-gear embodying my invention, the parts being in the normal position or at rest on the center. Fig. 2 is a similar section, the parts 15 being in action or in the position they occupy when under draft.

Like symbols refer to like parts wherever they occur.

My invention relates to that class of draft-gear commonly termed "friction draft-gear," 20 wherein the spring-resistance to the movement of the draw-bar in draft and buffing is augmented and modified by frictional resistance, induced by the combination, with the 25 draw-bar, of friction slides or plates yieldingly or spring supported of the general character covered by my Letters Patent No. 423,727, granted March 18, 1890, and the present invention may be considered as an improvement 30 thereon. In this class of draft-gear as at present constructed the typical combination of elements may be said to be a plurality of connected reverse inclines (one or more for draft and one or more for buffing) 35 combined and coacting with a similar connected series of spring-supported inclines. As a result of such a construction and combination there necessarily exists loss of contact (or space) between either the draft or the 40 buffing slides, according to whether the draw-bar is pulled out or forced in, and unless the reversing is very slow or gradual, which seldom occurs in service, the draft-gear is subjected to violent shocks and jars which tend 45 greatly to its deterioration and destruction.

To overcome these objections is the object of my present invention; and to this end, generally stated, it consists in the combination, with a draw-bar, of independently-yielding "draft" and "buffing" friction-slides so arranged that all the friction-faces are maintained in constant contact during the opera-

tion of the draw-bar, and such a construction embodies one feature of my invention.

In carrying out my invention I prefer to 55 combine with a plurality of fixed reversely-arranged inclines located on the draw-bar a series of independently-yielding or spring-supported reversely - arranged friction - inclines mounted on the car-body; but it will 60 be evident to the skilled mechanic that the location of the fixed and yielding inclines may be reversed, and either of said arrangements are contemplated by me and form a secondary 65 feature of my invention.

There are other minor features of invention, all as will hereinafter more fully appear.

I will now proceed to describe my invention more fully, so that others skilled in the art to which it appertains may apply the same. 70

In the drawings, A indicates the draw-bar, (partly broken off,) and a a' friction-inclines fixed thereon. In the present instance the draw-bar is shown as a strap-bar, and the friction-inclines a a', which may be integral 75 and constitute a cored casting A' or otherwise constructed, as preferred, are rigidly secured to the draw-bar A by a tail-strap R, though, if preferred, the well-known tail-bolt construction may be adopted. 80

b b' indicate independently - yielding inclines arranged on opposite sides of the draft-bar and coacting with the respective friction-inclines a a' of the draw-bar A. For the purposes of this description I will term the inclines b the "yielding draft-slides" or "yielding friction-plates" and those marked b' the "yielding buffing-slides" or "yielding friction-plates," it being understood that the inclines a a' or draft and buffing slides, which 85 coact with said yielding draft and buffer slides, are or may be fixed with relation to each other. The draft and buffing inclines are reversely arranged, and in case of the independently-yielding inclines (marked b b') 90 are preferably formed with cups or sockets c, adapted to slide within housings or guide-boxes D and to include springs C C', which maintain a constant contact between the several inclines or friction-plates a b and a' b'. 95 100

D indicates housings or guide-boxes for the reception of the telescoping cups or sockets of the friction plates or inclines, and said boxes may be divided into compartments by

the partition or guide wall *d*, or, if preferred, a separate housing or guide-box may be provided for each friction-plate of the series, and in either case the construction may be such 5 as to utilize also the friction between the cup or socket *c c* and the guide-box *D*. The guide-boxes or housings *D D* are preferably connected by an intermediate web or plate *D'*, which may be cast integral therewith, the 10 ends of the boxes *D D* being closed by heads *D' D'*, bolted thereto, or in other suitable manner.

C C' indicate nested springs within the cups or sockets *c c* of the friction-slides and having 15 their bearings on the heads *D' D'* of the guide-boxes or housings *D D*. For purposes of illustration I have shown nested springs *C C'*, the outer (shorter and stronger) of which, *C*, is to assume the load while the friction- 20 slide is in operation, while the inner or lighter spring *C'* is what may be termed a "follower-spring," and is constantly under compression to insure and maintain the contact of the friction slides or inclines at all times. It will 25 be evident, however, to one skilled in the art that a single spring under constant compression may be substituted for the nested springs, but will not be so effective or desirable.

The housings or guide-boxes *D D* are 30 secured to the draft-timbers of a car by bolts and straps (not shown) or in other of the several well-known suitable ways of connecting draft-rigging to the bed of the car.

The construction being substantially such 35 as hereinbefore set forth, the draft-rigging will operate as follows: Draft being made on the draw-bar *A*, the friction draft-inclines *a* thereon coacting with the yieldingly or spring-supported friction-slides *b* will force 40 back the springs *C C'* of said slide, thus maintaining a constant spring-applied frictional resistance to the outward movement of the draw-bar *A*, (see Fig. 2,) while the springs of the reverse and independently-moving inclines *b b'* will cause the advance of the 45 buffing-inclines and maintain their contact with the corresponding buffing-inclines *a'* on the draw-bar *A*, so that on the reversal or inward movement of the draw-bar *A*, as in 50 buffing, the buffing friction-inclines and their springs will at once assume the load without shock or jar, and the draft friction-slides *b* will thereafter follow and maintain contact with their friction-plates *a* during the inward 55 or buffing action of the draw-bar in like manner as did the buffing friction-slides *b'* with the friction-plates *a'* during the outward movement of the draw-bar *A*.

For purposes of illustration the construction shown and described by me has embraced but two sets of draft and buffing plates oppositely placed with relation to the draw-bar; but it is evident that one of said sets might be replaced by parallel friction- 65 plates on one side of the draw-bar or that the friction-surfaces may be multiplied to any extent permissible and practicable with a

given length of draw-bar without departing from the spirit and scope of my invention, provided only that the yielding buffing friction-plates and the yielding draft friction- 70 plates be independent of each other in their movement and be yieldingly supported so as to maintain a constant contact of both the draft and the buffing friction-plates. 75

Having thus described my invention, what I claim, and desire to secure by Letters Patent, is—

1. In a friction draft-gear, the combination with a draw-bar having a draft incline or slide 80 and a buffer incline or slide, of separate draft and buffer slides which coact therewith said latter slides independent of each other, and means for yieldingly supporting one of said buffer-slides and maintaining constant contact 85 between the buffer-slides during the operation of the draw-bar; substantially as and for the purposes specified.

2. In a friction draft-gear, the combination with a draw-bar having a draft incline or slide 90 and a buffer incline or slide, of separate draft and buffer slides which coact therewith said latter slides independent of each other, and means for yieldingly supporting one of said draft-slides and maintaining constant contact 95 between the draft-slides during the operation of the draw-bar, substantially as and for the purposes specified.

3. In a friction draft-gear, the combination with a draw-bar having a draft incline or slide 100 and a buffer incline or slide, of separate draft and buffer inclines or slides which coact therewith said latter slides independent of each other, and means for yieldingly supporting one of said draft-slides and one of said buffer- 105 slides and maintaining constant contact between all of said buffer-slides and all of said draft-slides during the operation of the draw-bar, substantially as and for the purposes specified. 110

4. In a friction draft-gear, the combination with a draw-bar having a draft-incline and a buffing-incline, said inclines reversely arranged, of separate draft and buffer slides which are also reversely arranged and coact 115 therewith said latter slides independent of each other, and springs which yieldingly support said separate draft and buffing slides, substantially as and for the purposes specified. 120

5. In a friction draft-gear, the combination with a draw-bar of a draft incline or slide and a buffing incline or slide, separate draft and buffing slides which coact therewith and are independently movable, and springs for yieldingly supporting said separate and independently-movable draft and buffer slides said springs being under constant compression whereby constant contact is maintained between all the draft and all the buffer slides, 125 substantially as and for the purposes specified. 130

6. In a friction draft-gear, the combination with a draw-bar having fixed reversely-ar-

ranged inclines, of separate draft and buffing slides each of which is yieldingly supported and movable independently of the other, said latter slides being also reversely arranged, 5 and a housing provided with a separate compartment for each of said independently movable draft and buffing slides, substantially as and for the purposes specified.

In testimony whereof I affix my signature, in presence of two witnesses, this 5th day of 10 November, 1900.

HARRY C. BUHOUP.
